UNITED STATES PATENT OFFICE.

CHARLES A. MEUNIER, OF GREAT NECK, NEW YORK.

HANGER.

Application filed May 6, 1922. Serial No. 558,878.

To all whom it may concern:

Be it known that I, CHARLES A. MEUNIER, a citizen of the United States, and resident of Great Neck, Long Island, in the county 5 of Nassau and State of New York, have invented a new and Improved Hanger, of which the following is a full, clear, and exact description.

My invention relates to a gutter hanger, 10 and aims to provide certain new and useful improvements in connection with a device of this character.

It is an object of the present invention to provide a gutter hanger which may be constructed of copper or any other suitable metal, and which hanger will incorporate sufficient rigidity to withstand any strains to which it is subjected without having its body distorted.

It is a further object of the present invention to provide an extremely simple form of connection between the strap and hanger which will incorporate absolute rigidity although the connection may be established by 20 means of a minimum amount of labor.

A still further object of this invention is that of providing a device of the type stated which may pierce the body of the gutter to which it is associated as in conventional construction, but in which this piercing may be effected without any distortion of the parts contrary to conventional construction, in which these parts buckle during this operation.

Still another object of this invention is that of providing a hanger incorporating the features aforementioned which will also serve to support the gutter in such a manner as to preclude any danger of the latter becoming detached from the body of the former.

With these and further objects in mind my invention includes essentially a hanger comprising a body which engages the gutter adjacent its ends together with a strap for supporting the body of the hanger.

In the attached sheet of drawings one practical embodiment of my invention has been shown, and in these drawings it will be 50 seen that:

Figure 1 is a sectional side view of a conventional type of gutter and showing my improved hanger in association therewith.

Figure 2 is a plan view taken along the 55 line 2—2 and in the direction of the arrows illustrated in Figure 1.

Figure 3 is an enlarged sectional transverse view taken along the line 3—3 and in the direction of the arrows illustrated in Figure 1.

Figure 4 is a further enlarged sectional view taken along the line 4—4 and in the direction of the arrows indicated in Figure 2, and

Figure 5 is a perspective view of a detail 65 of construction showing the parts of the hanger prior to its application to the gutter.

In these views it will be seen that the reference numeral 10 indicates the gutter proper having one of its side edges beaded 70 as at 11, in accordance with conventional construction, the said gutter being supported by my improved type of hanger which is in turn suspended by the strap 12.

It will be noted that this hanger conveniently includes a body 13 extending transversely to the body of the gutter and has its ends bent as at 14, so as to incorporate rigidity. The body of the hanger is further extended beyond its bent portions, and terminates at one of its ends in a hook 15, adapted to encircle the bead 11 of the gutter 10. The opposite end of the hanger is further bent upwardly as at 16 to extend parallel to the inner face of the gutter 10, outwardly as at 17 to bridge over the upper edge of the same, downwardly as at 18 to extend flush against the outer face of the gutter, and inwardly in the form of a spike 19 which latter portion is adapted to project 90 through the gutter.

With respect to this last described construction it will be noted that the spike 19 or inwardly extending portion is adapted to project in its final position, through an 95 opening 20 in the upwardly extending portion 16. Thus assuming that the hook 15 is applied to the bead 11, and the opposite end of the hanger has its parts disposed in the position shown in Figure 5, that the 100 edge of the gutter may be inserted into the space existing between the upwardly extending portion 16, and downwardly extending portion 18 of the hanger body. Subsequent to the positioning of these parts, the application of proper tools to the same will cause the spike or inwardly extending portion 19 to pierce the body of the gutter adjacent the edge of the same. However the outer face of the upwardly extending portion 16 will act as an anvil during 105 the operation of the parts. Thus contrary

to conventional construction in which the gutter is not supported during the piercing of the same, and due to which action the body becomes distorted, it will be appreciated that by means of my improved construction the gutter body is properly held to prevent any bending of the same adjacent the point at which it is pierced, and after the parts have been brought to their final position, i. e., the position shown in Figures 1, 2 and 4, the inwardly turned portion or spike 19 of the hanger will rest upon the upper face of the body 13 so that no detachment of the hanger from the gutter can occur without deliberately forcing the upwardly and downwardly extending portions 16 and 18 respectively, apart.

Now with a view of providing a rigid connection between the strap and the hanger, which connection may be established by means of the expenditure of a minimum amount of labor, it will be noted that the body of the strap is turned, as at 21, so that the body of the same lies flush against the body 13 of the hanger. Attention being particularly invited to Figures 1 and 3, it will be noted that the end of the strap, however, is bent at right angles to its body as at 22, the upper face of this latter portion bearing against and being in intimate contact with the lower edge of the body 13, and a rivet or other suitable fastening member 23 is now passed through the strap 12, and the body 13 to retain the same in applied position with respect to each other.

Thus incident to this connection which may be produced at a relatively nominal figure, it will be understood that any move-

ment of the hanger either transversely or longitudinally of the strap is precluded, first incident to the engagement between the face of the hanger and the face of the strap, and secondly by virtue of the engagement existing between the end 22 of the strap and the edge of the hanger, thus providing an extremely simple form of connection by means of which the results desired are achieved.

Thus it will be appreciated that all of the objects of this invention have been accomplished, and it will further be understood that numerous modifications of structure might readily be resorted to without in the least departing from the scope of my claims; which are—

1. A gutter hanger including in combination a body adapted to be attached to a gutter, a strap for suspending said body, said strap including a body having its face flush against the hanger body, the end of said strap being bent to engage the edge of said hanger body, and means extending through said strap and hanger for retaining the same in this position.

2. A gutter hanger including a hanger body adapted to support a gutter, a strap twisted to have one of its lower end portions lie flush against the body of said hanger and bent at the lower end of said end portion to provide an extension substantially at right angles to said end portion, and means extending through said strap and hanger body for retaining the parts in intimate contact with the upper face of said extension engaging the lower edge of said hanger body.

CHARLES A. MEUNIER.
